UNITED STATES PATENT OFFICE.

CHARLES J. HEUSER, OF PATERSON, NEW JERSEY.

MEANS FOR ELIMINATING VAPOR AND PREVENTING CONDENSATION AND FOR VENTILATION.

Application filed October 4, 1921. Serial No. 505,427.

To all whom it may concern:

Be it known that I, CHARLES J. HEUSER, a citizen of the United States, residing at Paterson, in the county of Passaic and State 5 of New Jersey, have invented new and useful Improvements in Means for Eliminating Vapor and Preventing Condensation and for Ventilation, of which the following is a specification.

10 This invention relates to new and useful improvements in the construction of dye-houses whereby vapors are eliminated directly from the tub room of the building.

In accordance with my invention inner 15 and outer roofs are arranged in spaced relation so as to form an insulating air space therebetween and means are provided for regulating the temperature of the air contained therein in order to prevent condensation on the inner roof.

20 My invention also aims to provide a dye-house of simple, economical and durable construction which will afford healthful working conditions for the employees.

25 The invention is described in the following specification in connection with the accompanying drawings, in which —

Figure 1 is a plan view of a portion of the structure housing the tub room.

30 Figure 2 is a cross-section of a structure embodying a number of tub rooms and working spaces.

Figure 3 is a longitudinal section through a tub room.

35 The building proper consists preferably of standard structural steel parts such as supporting columns 10 of H or I section, and trusses 11 and 12 of appropriate design for supporting respectively the outer roof 13 and inner roof 14 over the tub room 15, and the roof 16 over the work room 17.

40 As its name implies the tub room is provided with a number of tubs or kettles 18 adapted to contain the dye solution or mordant. These tubs are arranged in two rows which are placed along opposite sides of the tub room immediately adjoining work rooms 17, so that the two rows of tubs are accessible from different work rooms. A steam pipe 19 is placed immediately above each row of tubs and the dye solutions contained in the tubs are maintained at the de-

sired temperature by suitable heating coils or pipes (not shown) which are fed from the main supply pipe 19.

55 The truss 11 is of such formation that the inner and outer roofs 14, 13 taper upwardly, giving a cupola effect. A vent 21 communicates with the upper portion of the tub room through a suitable passageway 22, 60 which pierces the inner roof. In fact, two of these vents and cupola roofs are shown in Figures 1 and 3 in connection with a single tub room, but the number of vents employed is, of course, dependent upon the 65 number of tubs used in one row. The passageways 22 are enclosed by walls 23 which traverse the insulating space 24 between the inner and outer roofs. This space or chamber 24 is tightly enclosed by the 70 outer roof of any suitable water-proof material, the inner roof of special construction, and the side walls 25.

75 Conduits 20 are located in the chamber 24 in opposite lower corners thereof and a plurality of angularly disposed outlets 26 pierce the inner roof 14 and direct a flow of heated air towards the tubs 18. Each conduit 20 extends the full length of a row of tubs and is connected at one end with a 80 suitable blower (not shown) for supplying heated air thereto. The vents 21 may also be provided with fans (not shown) which should be arranged to draw off equally from the entire area of the tub room, the air introduced through the outlets 26.

85 The air contained in insulating space 24 is maintained preferably at a temperature of about 60° F., and when the outside temperature is sufficiently low, this desired temperature is obtained by admitting heated air from the conduit 20 to the chamber 24 through suitable valve controlled openings 27 or the like.

90 The inner roof 14 is built up of plaster board 28 secured to the steel frame of the truss 11, a layer of felt 29 placed on the plaster board and asbestos wood 30 which is applied over the felt.

95 The air chamber 24 keeps the inner roof 14 at a suitable temperature regardless of any low outside temperature owing to the insulating effect of the air contained therein, the temperature of which is controlled

by admitting air from conduit 20, as above explained. The steam and other vapors arising from the tubs or kettles 18 immediately strike the steam pipe 19 and come in contact with the heated air from outlets 26 which evaporate the moisture and the air current produced by the outlet fans conveys the resulting gases to the vent 21. All vapors are thus rapidly eliminated from the tub room without even entering the work room, thereby eliminating uncomfortable and injurious atmospheric conditions which otherwise would exist. The construction of the inner roof in connection with the insulating chamber 24 prevents condensation and eliminates damage to goods in course of treatment which otherwise might occur owing to condensation and moist atmospheric conditions. Furthermore the elimination of various vapors and moisture prolongs the life of the structure and consequently avoids the frequent replacement of dyehouses, which heretofore have deteriorated very rapidly.

During the hot weather of summer months the conduits 20 may be used to supply relatively cool air whereby the arrangement becomes a ventilating system and at the same time acts to eliminate vapors from the tub room.

It will be understood that the particular construction described and shown has been chosen for illustrative purposes merely and that the invention as defined by the claims hereunto appended, may be otherwise em-

bodied and applied without departing from the spirit and scope thereof.

I claim:

1. In a dyehouse structure including side walls and a series of vats positioned adjacent each side wall, a pyramidal insulated ceiling section supported by the side walls, the sides of said section converging upwardly to form with said structure an insulated air space above said section, said section being truncated, an outlet duct at the truncated portion through said air space, said vats being coincident with the lower edges of the section, means for heating said insulated air space, said means having a plurality of outlets for directing a stream of heated air to each vat.

2. In a dyehouse structure including side walls and a plurality of series of vats positioned adjacent each side wall, a plurality of pyramidal insulated ceiling sections supported by the side walls, the sides of said sections converging upwardly to form with said structure insulated air spaces above said sections, said sections being truncated, outlet ducts at the truncated portions through said air spaces, said vats being coincident with the lower edges of the sections, means for heating said insulated air spaces, said means having a plurality of outlets for directing a stream of heated air to each vat, and an additional heating means positioned over each series of vats.

CHARLES J. HEUSER.
